(57) **CLAIM**

The ornamental design for an automobile body, as shown and described.

DESCRIPTION

FIG. 1 is a front view of an automobile body constructed according to our novel design;

FIG. 2 is a right side view thereof;

FIG. 3 is a top plan view thereof; and,

FIG. 4 is a rear view thereof.

The broken lines showing of environmental structure in FIGS. 1-4 of the drawings are for illustrative purposes only and form no part of the claimed design.

Left side view has been omitted because it is substantially symmetrical to the right side view shown in FIG. 2.
